ATTORNEY

UNITED STATES PATENT OFFICE.

GEORGE J. FLEURE, OF BROOKLYN, NEW YORK.

FOOT-OPERATED PUMP FOR PNEUMATIC TIRES.

1,397,416.

Specification of Letters Patent. Patented Nov. 15, 1921.

Application filed May 28, 1920, Serial No. 385,039. Renewed October 11, 1921. Serial No. 507,156.

To all whom it may concern:

Be it known that I, GEORGE J. FLEURE, citizen of the United States, residing at Brooklyn, in the county of Kings and State 5 of New York, have invented new and useful Improvements in Foot-Operated Pumps for Pneumatic Tires, of which the following is a specification.

This invention relates to improvements in 10 foot pumps for pneumatic tires and the like and the principal object is to produce a simple and effective device of this type.

In describing my invention reference may be had to the accompanying drawing consisting of 1 sheet in which:—

Figure 1 is a side elevation of my improved foot pump.

Fig. 2 is a vertical longitudinal sectional view of the same.

Fig. 3 is a vertical sectional view taken substantially in line 3—3, Fig. 1.

Fig. 4 is a detail view of the pump piston and its operating connections.

Like reference numerals refer to like parts 25 in the several views.

In general terms my pump comprises a cylinder having a piston seated therein and adapted to be reciprocated by the operation of a treadle or foot lever which is forced 30 down by the foot of the operator and is automatically returned to a normal elevated position by a spring or other automatic means.

Referring more particularly to the drawings, 1, represents a pair of side frame members 35 to which are secured by bolts or any other desirable means two blocks 2 formed so as to provide an aperture in which is snugly seated the pump cylinder 3. A piston 4 is adapted to reciprocate in said cylinder in a 40 well known manner for forcing air through the tube or nozzle 5 to the tire or other article to be inflated. The piston rod 6 is the central rod of a trident shaped member having two outer rods 7 as shown in Fig. 4.

Each of the rods 7 is connected at its free 45 end to a respective block 8 working in a longitudinal aperture or track 9 formed in a respective one of the side frames 1.

A U-shaped treadle or foot operated member 10 provided with a stiffening rod 11 has 50 its side arms each connected with a respec-

tive one of said sliding blocks 8. A pair of links 12 are secured to the side members 1 upon respective sides of the pump and have the other ends pivotally secured to respective sides of the U-shaped member 10. Springs 13 are seated in the apertures 9 between the end wall thereof and the respective block 8.

The operation of this device is as follows: 60 The foot is placed on the free end of the member 10 and this member is then forced down. The connection of the member 10 with the links 12 causes the member to swing forwardly or to the right in Fig. 1 to the 65 dotted line position therein shown, carrying with it the sliding blocks 8 which in turn draw with them the rods 7 and thereby operate the piston rod 6 to force the piston toward the front end of the cylinder thereby 70 ejecting the air through the nozzle 5.

While I have described what I deem to be the most desirable embodiment of my invention, it is obvious that various details are susceptible of change without in any way 75 departing from the spirit of my invention; and I therefore do not wish to be considered as limiting myself to the exact details of the embodiment herein shown and described nor to anything less than the whole of my invention as herein set forth and as hereinafter more particularly pointed out in the claims.

And now having described my invention what I claim as new and desire to secure by Letters Patent is:—

1. In a device of the class described, the combination of a cylinder, a tribrachial member, a piston head secured to the one of the branches of said member, a main frame for supporting said cylinder, and slides secured 90 to each of the other branches of said member, and mounted in apertures formed in said frame.

2. In a device of the class described, the combination of a cylinder, a tribrachial member, a piston head secured to the one of the branches of said member, a main frame for supporting said cylinder, slides secured to each of the other branches of said member, and mounted in apertures formed in said 100 frame, and operating mechanism for operating said slides.

3. In a device of the class described, the combination of a cylinder, a tribrachial member, a piston head secured to the one of the branches of said member, a main frame 5 for supporting said cylinder, slides secured to each of the other branches of said member, and mounted in apertures formed in

said frame, operating mechanism for operating said slides, and means for returning said slides to normal position.

10

In testimony whereof I have affixed my signature.

GEORGE J. FLEURE.
